UNITED STATES PATENT OFFICE.

SYDNEY J. MURTON, OF SEATTLE, WASHINGTON.

WASHING DEVICE.

1,178,817.

Specification of Letters Patent.

Patented Apr. 11, 1916.

Application filed September 9, 1915. Serial No. 49,665.

To all whom it may concern:

Be it known that I, SYDNEY J. MURTON, a subject of the King of Great Britain, residing at Seattle, in the county of King and State of Washington, have invented a certain new and useful Improvement in Washing Devices, of which the following is a specification.

My invention relates to improvements in washing devices, and the object of my improvements is to provide a hollow walled receptacle which shall be adapted to direct numerous jets of water against all portions of the surfaces of an object disposed within said receptacle whereby such surfaces may be subjected to the cleansing effect of the water thus impinging thereon, said water being conducted through a conduit from a source of water under pressure into the space between said hollow walls thence through numerous minute holes that extend through the inner surface of the receptacle to issue therefrom in the form of many jets directed in converging lines; and a further object of my improvements is to make such device of a form that will adapt it for the special purpose of washing ice cream scoops, ladles, spoons, and like utensils that may be disposed therein. I accomplish these objects by devices illustrated in the accompanying drawings wherein—

Figure 1 is a view in vertical mid-section of one form of a structure embodying my invention with a utensil to be washed disposed therein, which utensil is shown by a view in side elevation, and Fig. 2 is a view of parts of the same in horizontal section on broken line π , π of Fig. 1.

Referring to the drawings, throughout which like reference numerals indicate like parts, a cast metal base 3 of circular form is provided with an upwardly extended annular flange 4 integral therewith and with an integral boss 5 which extends upwardly from the central portion of said base 3 in a position concentric with the surrounding annular flange 4 whereby is formed an annular recess 6.

The boss 5 is provided with a concentrically disposed passageway 7 that extends vertically therethrough; and screwed into the lower end of said passageway 7 is a waste pipe 8 that may be extended to a desired point of disposal of waste water.

Fixed in the upper end portion of the passageway 7 is a nipple 10 which is integral

with the convex bottom of the inner one of two members 11 and 12 which form the hollow wall of a cup-like receptacle, through which nipple 10 water may pass from said receptacle into the waste pipe 8.

The upper portion of the inner member 11 is formed to have an outwardly extended flange 13, to the outer edge of which is joined the upper end edge of the outer member 12, while the lower end portion of said outer member 12 is provided with a flange 14 which is disposed to surround and make a water tight joint with the periphery of the upper portion of the annular flange 4; thus the inner member 11 and the outer member 12, together with the cast metal base 3 and its integral parts 4 and 5, form a receptacle whose surrounding wall is provided with a hollow space 15 and such receptacle is provided with an outlet passageway 7 through the central portion of its bottom through which water may escape into a waste pipe, as waste pipe 8.

The inner member 11 is perforated with many very small holes, as holes 16, which extend from the space 15 (between the members 11 and 12) into the interior of the receptacle, said holes 16 being evenly distributed throughout the extent of the cylindrical portion of said member 11 and throughout much of the concavo-convex bottom portion thereof, but for convenience of drawing I have shown only a few of such holes 16.

Extending through the annular flange 4 at opposite points therein are two pipes 17 and 18, respectively, one of which may be extended to a source of cold water under pressure, while the other may be extended to a source of hot water under pressure, whereby such water may flow under pressure to find its way into the space 15 between the members 11 and 12, thence through the small holes 16 in the form of numerous jets to impinge against the surfaces of an object that may be placed within the receptacle, as, for instance, an ice cream scoop 19, which rests upon a grating or perforated disk 20 that is supported by an annular shoulder 21 formed in the member 11 near its bottom end and above the entrance to the passageway through the nipple 10, which perforated disk 20 serves to prevent said scoop 19 from obstructing said entrance to said passageway.

The flow of water through the pipes 17 and 18 may be controlled by hand operated

valves 22 and 23, respectively, thus to use either cold water or hot water or a mixture of cold water and hot water in amounts as desired. Under some conditions of use it 5 may be desired to use only cold water or only hot water, in which case one of the pipes 17 or 18 may be dispensed with and the hole into which it is screwed may be closed with a plug in a well known manner. 10 Obviously changes may be made in the forms, dimensions and arrangement of parts of my invention without departing from the spirit thereof.

What I claim is:

15 A washing device of the class described embodying inner and outer receptacles of

substantial cup-shape arranged one within the other, a supporting base for the receptacles, means for supplying water to the base of the outer receptacle, the inner receptacle 23 being perforated to permit the passage of water from the outer receptacle to the inner receptacle, and a nipple connection between the lower central end of the inner receptacle and the base constituting an outlet therefor. 25

In witness whereof, I hereunto subscribe my name this 7th day of August A. D., 1915.

SYDNEY J. MURTON.

Witnesses:

FRANK WARREN,
A. HASKINS.
